G. A. BURNHAM.

OIL SWITCH.

APPLICATION FILED MAY 26, 1917.

1,399,460.

Patented Dec. 6, 1921.

UNITED STATES PATENT OFFICE.

GEORGE A. BURNHAM, OF SAUGUS, MASSACHUSETTS, ASSIGNOR TO SEARS B. CONDIT,
JR., OF BROOKLINE, MASSACHUSETTS.

OIL-SWITCH.

1,399,460.

Specification of Letters Patent.

Patented Dec. 6, 1921.

Application filed May 26, 1917. Serial No. 171,274.

To all whom it may concern:

Be it known that I, GEORGE A. BURNHAM, a citizen of the United States, residing at Saugus, in the county of Essex and State of 5 Massachusetts, have invented an Improvement in Oil-Switches, of which the following is a specification.

My invention relates to electric switches, and has specific reference to double-throw 10 switches employed for the control of induction motors, and in which the contacts are made and broken under oil and is intended as an improvement on the electric switch shown in my application Patent No. 1,312, 15 777, dated Aug. 12, 1919.

An object of my invention is to provide a switch of the type specified with trip coils and with latch mechanism so associated with the movable switch members and operating 20 handle that when the switch handle has been moved to its running position, the latch mechanism tends to maintain the handle and the movable switch member in this position until actuated, because of an excess current 25 flow in the trip coils, to operatively disconnect the handle and movable switch member, whereupon the switch member moves to open position and the handle independently moves to neutral position; that will 30 permit the switch member to move to open position upon effective energization of the trip coils even though the operating handle is manually maintained in the running position; and that will permit the switch member 35 to be moved to open position by the manual movement of the switch handle to neutral position.

A further object of my invention is to provide means whereby the switch is normally 40 maintained in a neutral position against movement in one direction, and whereby the switch must be moved into the starting position and then must be rapidly moved into the running position.

45 A further object of my invention is to provide a switch that is cheap and durable in construction and reliable in operation.

Certain features herein set forth and illustrated are also disclosed in my co-pending 50 application Serial No. 169,227, filed May 17, 1917.

Figure 1 is an elevation, partly in section, of a switch embodying my invention.

Fig. 2 is an elevation of the switch operating mechanism. 55

Fig. 3 is a plan view of the switch operating mechanism.

Fig. 4 is a detail, in elevation, of the switch operating handle and latch.

As here shown, the switch in which my 60 invention is incorporated is similar to that shown in my said application Patent No. 1,312,777, dated Aug. 12, 1919, comprises a base 10 of slate or other insulating material, which is secured between a lower tank or 65 receptacle 11, adapted to contain oil and to inclose the stationary and movable switch contacts, and an upper casing 12 which incloses the switch operating mechanism. The tank 11, casing 12 and base 10 are clamped 70 or secured together by means of wing bolts 13, fastened to tank 11, and engaging lugs on casing 12. A cover 14 incloses the top of casing 12 and is secured thereto by screws.

Movable switch members, consisting of a 75 plurality of flexible spring strips 15, terminating in detachable contact members 16, depend from base 10 into the oil of container 11, and are secured to said base 10 by bolts 17, and a plurality of stationary contact members 18 and 19 also depend into the oil of container 11 and terminate in detachable contacts 20 and 21, equally disposed on each side of the normal or open circuit position of the movable switch members. Contact members 18, 19 are secured to base 10 80 by bolts 22 and 23.

Spring strips 15 are secured intermediate the lengths thereof between two bars of insulating material 24 which are clamped or 90 fastened together by screws 25 which also serve to secure a metal plate 26 to the top bar 24. Metal plate 26 has an ear 27 provided with a perforation in which the hooked end 28 of the switch operating rod 29 is 95 inserted. Operating rod 29 extends through an opening 31 in base 10 and the vertical movement of said rod is employed to move the clamp formed of bars 24 and flex the strip 15 and thus move the contact members 100 16 secured thereto into engagement with one or the other of the stationary contacts 20 and 21.

Rod 29 is a component part of the operating means for the switch, and as here shown, 105 has its upper end provided with an eye 30

which receives the crank portion 32 of a shaft 33 arranged horizontally in the top casing 12 and adapted to oscillate in bearings 34 arranged in opposite side walls of casing 12.

A spring 35 is arranged on the rod 29, between the eye 30 and the base 10, which is normally inert, but which is compressed by a downward movement of the rod. The 10 lower end of spring 35 rests on a cover plate 36 for the hole 31 in base 10, and the rod extends through a hole in said cover plate, a function of the spring 35 being to maintain said cover plate in position on said 15 base over said hole 31. As the rod 29 is moved in a vertical direction it is also laterally displaced in a slight amount in the hole 31 and consequently, the cover plate will follow the movements of the rod but 20 in all positions will completely cover the hole and thus prevent access of oil and oil vapor to the upper chamber.

Shaft 33 is provided with a second crank 37, angularly displaced from the crank 32 25 and a link 38 is pivoted to said second crank 37. Link 38 comprises one member of a toggle of which the second member is an arm 39 secured to a shaft 40 which has a bearing at 41 in a wall of the top casing 30 12 and has an operating handle 42 secured to its outer end and the straightening of which toggle serves to maintain the switch in its closed position.

Link 38 is provided with a slot 43 which 35 has a recessed portion or notch 44. Arm 39 carries at its extremity a pin 45, which, in an operative position of the switch, is in engagement with notch 44 of link 38.

A latch 46, pivoted at 47 to link 38 and 40 provided with an arm 48 and a bent portion 49 adapted to be engaged by the pin of the trip coils to cause the opening of the switch under overload, has a second arm 50 disposed under pin 45 of arm 39 and normally 45 serves to maintain said pin in the notch 44 of link 38, whereby a movement of said arm 39 may be transmitted through link 38 to the shaft 33 to operate the movable switch members, and arm 50 is provided with a 50 curved face 51 conforming to the surface of pin 45 for the secure engagement of arm 50 with pin 45.

Link 38 has an extension 54 terminating in a bent projection 52 against which the 55 arm 48 of latch 46 is adapted to rest to limit movement of the latch in one direction.

Operating handle 42 is secured to shaft 40 in an angular relation with the arm 39 in operative connection with link 38 and has 60 its movement limited between two stops or pins 55 secured in the wall of the casing 12.

In the normal, or open position of the switch, the handle 42 hangs vertically downward in its neutral position and the arm 39 65 and link 38 occupy the relative positions

shown in Fig. 1, with pin 45 of arm 39 in slot 43 of link 38. As handle 42 is moved to the right or starting position, pin 45 travels toward the end of slot 43, displaces the latch 46, and enters the notch 44 of said 70 slot, whereupon the further movement of switch handle 42 is transmitted through link 38 to the shaft 33 which is rotated, and causes a movement of the movable contact members 16 into contact with the stationary 75 or starting contact members 20. After the motor has acquired its normal speed, the switch handle 42 is moved to the opposite or running position, and as pin 45 is maintained in notch 44 by latch 46, the movement of arm 39 is transmitted through 38 to crank shaft 33 which is rotated, and switch contacts 16 are brought into contact with the stationary running contacts 21.

In the extreme or running position of the 85 switch, the toggle formed of links 38 and arm 39 is slightly offset, being maintained in such position by the compression of spring 35, and prevented against movement to further offset position by the engagement 90 of handle 42 with pin 55.

Upon the occurrence of a sufficient overload, the pin 56 is actuated by sufficient energization of the trip coils hereinbefore described, and operates to strike the bent portion 49 of latch 46 and impart an angular movement to said latch which serves to swing arm 50 from engagement with pin 45 of arm 39 sufficient to cause its disengagement with pin 45, whereupon, the restraint 100 being removed from spring 35 and contacts 16, said contacts are moved to open position and the crank shaft 33 is rotated to its neutral position, the handle 42 with its associated arm 39 independently falling, by its 105 weight, to neutral position.

Switch members 15 can be moved from running to neutral position by a movement of the handle 42 to neutral position, since pin 45 of arm 39 is maintained by latch 46 110 in notch 44, and notch 44 and the curved face 51 of arm 50 of latch 46 serve as a pivotal bearing for pin 45.

A frame 57 depending from base 10 and secured thereto by bolts 57' supports the 115 solenoids or trip coils 58, which are independently connected in series with two of the stationary contact members. The solenoid cores 58 operate in tubes 59 and said tubes are provided with vertical slots 59^a 120 through which project pins 60 which are fastened to the said cores 58^a. Said pins are adapted to engage with the flange 61 of trip pin 56 upon sufficient energization of said trip coils to move said pin into engagement 125 with the latch 46, whereby to trip said latch and cause the movement of the switch to open position.

Tubes 59 are provided at their lower extremities with spring sleeves or collars 62, 130

adapted to be clamped to said tubes by bolts 63, and are adjustable longitudinally upon said tubes, and, by engagement with pins 60 of the cores of trip coils 58, may vary 5 the position of said cores in said coils, and thereby vary the point at which said cores will be effectively energized to trip the latch.

The means whereby I normally maintain the switch in normal neutral position against 10 a movement of the switch to running position without first moving the switch to starting position comprises a curved latch 64, pivoted at 65 to the wall of the casing 12 adjacent handle 42 and in the path of movement 15 of a pin 66 in said handle. The lower face 67 of latch 64 is provided with a notch or depression 68 that normally engages pin 66 or handle 42, and normally prevents movement of said handle to the running position 20 of the switch. The arrangement of said notch 68 is such, however, that a movement of the switch handle to starting position is permitted. If the switch handle be now rapidly moved to the running position, 25 the component of downward velocity of the pin 66 of handle 42 is greater than that of the notch 68 in said latch, falling under the influence of gravity and consequently the pin 66 passes beyond the notch before the 30 latch has fallen sufficiently to admit of effective engagement of the notch 68 with pin 66, and consequently the switch is permitted to move into its running position.

I claim:—

- 35 1. An electric switch including a base, a receptacle adapted to contain oil secured to said base, flexible spring strips secured to said base and depending therefrom into the oil in said container and terminating in detachable contact members, said spring strips and contact members constituting movable switch members, two sets of stationary switch members secured to and depending from said base, detachable contacts thereon disposed in a vertical position on each side of said movable switch members, switch-operating means including a crank shaft, a trip coil secured to and depending from said base into the oil of said receptacle, an operating handle, toggle mechanism connecting said operating handle with said crank shaft, a latch associated with said toggle mechanism, said toggle mechanism and latch being so arranged that the switch members can be moved to open position upon effective energization of said trip coils with the operating handle manually maintained in running position, and that will permit a movement of said handle from running position to move said switch members from running position, and means associated with said handle whereby said handle is normally maintained in neutral position against a movement to running position, and whereby the operator is compelled to
- 40 move said handle to starting position and then rapidly move it into running position.
- 45 2. An electric switch including movable switch members, two sets of stationary switch members, operating means for said movable members including a crank shaft, an operating handle, members comprising toggle mechanism connecting said handle with said crank shaft, said members adapted to be operably disconnected, a latch associated with one member of said toggle mechanism adapted to hold said members operably connected, a trip coil associated with a stationary contact and adapted to move said latch upon effective energization of said coil to operably disconnect said toggle members, said latch and toggle mechanism being so arranged as to permit the movement of said handle in one position to move said movable switch members to contact with one set of stationary switch members, to permit the movement of said handle to a second position to move said movable switch member into contact with said second set of stationary switch members, to permit a movement of said handle from said second position to move said movable switch members from their corresponding position and to permit the independent movement of said movable switch members from said second position to a neutral position upon sufficient energization of said trip coil, regardless of the maintenance of said handle in said second position, and a latch for compelling a movement of said handle to said first position previous to its compelled rapid movement to said second position.
- 50 3. An electric switch including two sets of stationary switch members, movable switch members, switch operating means, an operating handle, toggle mechanism connecting said switch operating means and said handle, a latch pivoted to one of said toggle links and adapted for normal engagement with a component part of the other toggle link, whereby the two links are maintained in normal effective engagement, and means operable by a predetermined current flow to disengage said latch from the component part of said toggle link and cause a relative movement between the toggle links, whereby said toggle will be broken and the movable switch members moved to neutral disengaged position.
- 55 4. An electric switch including two sets of stationary switch members, movable switch members, switch operating means, an operating handle, members comprising toggle mechanism connecting said switch operating means and said handle, said members adapted to be operably disconnected, a latch pivoted to one of said toggle links and adapted to engage a component part of the other toggle link, whereby the two links are maintained in normal effective engagement, and

means operable by a predetermined current flow to disengage said latch from the component part of said toggle link and cause a relative movement between the toggle links, whereby said toggle will be broken and permit the independent movement of the movable switch member and operating handle to neutral position.

5. An electric switch including two sets of stationary switch members, movable switch members, switch operating means, an operating handle, toggle mechanism connecting said switch operating means and said operating handle, a latch pivoted to one of said toggle members and adapted to engage a component part of the other toggle member, said toggle members being normally disengaged but adapted to be moved into engaging position and maintained in said position by said latch during a movement of the switch handle to actuate the movable switch members into engagement with one set of stationary switch members and a subsequent movement of the handle to move the movable switch members into engagement with the second set of stationary members and to maintain said switch members in the latter position, and means operable upon a predetermined current flow to cause the disengagement of said latch with the component part of one of the toggle members, whereupon the toggle will be broken to permit the movement of the movable switch members to neutral disengaging position.
35. 6. An electric switch including two sets of stationary switch members, movable switch members, rocking means adapted to be operated in either direction from a neutral position to cause said movable switch members to engage one or the other set of stationary contact members, an operating handle adapted to be actuated to operate the rocking means, an arm carried by said handle, a pin on said arm, a link connected to said rocking means and having a slot in which the pin on said arm operates, said link and arm forming mechanism by means of which a movement of the operating handle in one direction serves to actuate the movable switch members into contact with one set of stationary switch members, and said link and arm forming a toggle that serves to lock the movable switch members into engagement with the other set of stationary contacts upon

movement of the operating handle in the opposite direction, said pin in said arm fitting into a recess in the slot of said link in the second position of the movable switch members, a latch pivoted to said link and having an arm normally tending to maintain said pin in the recess of the slot and adapted to be moved from engagement with said pin upon a predetermined current flow, whereby said toggle will be broken and said movable switch members moved to disengaged position.

7. An electric switch comprising stationary and movable switch members, operating mechanism comprising an operating handle, members forming toggle mechanism connecting said handle and movable switch members, said toggle members adapted to be operably disconnected for the tripping of the switch, a latch arranged to normally hold said members in operative condition, and electrically controlled means to operate said latch and operably disconnect said toggle members.

8. An electric switch having starting, running, and neutral positions, an operating handle, operating mechanism arranged to be normally disconnected from said handle and to connect therewith only upon movement of said handle from neutral to starting positions, and electrically-controlled means to disconnect said mechanism and handle to cause the switch to move from running to neutral positions.

9. A double throw electric switch comprising movable and two sets of stationary switch members, an operating handle and switch operating mechanism arranged to be operatively connected with said handle only upon a movement thereof from neutral to starting position, and thereafter connected for movement from starting to running position, and electrically controlled means to operatively disconnect the operating mechanism from the handle to permit the switch to open.

In testimony whereof, I have signed my name to this specification, in the presence of two subscribing witnesses.
